UNITED STATES PATENT OFFICE

HERMAN R. SMITH, OF DOUGLASTON, NEW YORK, ASSIGNOR TO RAYMOND CONCRETE
PILE COMPANY, OF NEW YORK, N. Y., A CORPORATION OF NEW JERSEY

COLLAPSIBLE CORE FOR CONCRETE PILES

Application filed February 27, 1926. Serial No. 91,024.

This invention pertains to collapsible cores for making concrete piles in situ, and is an improvement on the device disclosed in United States Patent No. 1,199,722, issued 5 September 26, 1916, to M. M. Upson and H. R. Smith.

The collapsible core disclosed in that patent comprises an inner member of the form of a shaft, either solid or hollow, extending 10 through the entire length of the device.

This shaft is provided with a plurality of spaced collars, in the shape of frustums of cones, which cooperate with corresponding surfaces attached to the sectional casing forming 15 the outer surface of the core. The outer casing is made in sections, each section being connected to the central shaft by short links, for a purpose to be described.

The central shaft is provided at its upper 20 end with a driving head and with devices to control the collapsing of the core after the driving is finished.

The core is expanded by raising it into vertical position and landing it on a timber, the 25 weight of the parts causing the cone shaped collars on the central shaft to act upon the co-operating surfaces of the outer core sections to expand them to full diameter. The core is held in expanded position by means of locking 30 dogs which hold the core sections up to the head. The shell is put on after the core is expanded, and is then driven to position.

After completion of the driving operation 35 the core is collapsed by mechanism in the head, actuated through a "false" driving head, which is in turn actuated by the hoisting effort applied to withdraw the core from the driven shell. The initial movement of the false head serves to actuate a lever system 40 which forces a movement of the central shaft relatively to the outer casing, thereby carrying the expanding collars of the shaft out of engagement with the outer casing and allowing the latter to collapse sufficiently to be 45 easily withdrawn from the shell by the short links connecting it to the central shaft.

Sometimes, during the driving operation, 50 the contacting surfaces of the central shaft and outer casing become so tightly wedged together that it is very difficult to draw them

apart, and the object of the present invention is to provide improved means to bring about such movement of central shaft and outer casing relatively to each other as is necessary in order to collapse the core after driving. 55

In some prior designs the collapsing mechanism comprises a lever system actuated by the false head when force is applied, while in other designs force is supplied by the driving hammer or jack. 60

My present invention discloses an improved device, hydraulically operated, and entirely independent of hoisting tackle or driving hammer. It is simple in design, cheap to manufacture, easy to keep in working order, 65 and may be operated manually or by power.

In the drawings,

Fig. 1 shows an interior view of a complete core embodying my device, with outer casing expanded. 70

Fig. 2 shows an interior view of a complete core embodying my device, with outer casing collapsed, and with hydraulic pump attached.

Fig. 3 is a cross section on line 3-3 of Fig. 2. 75

Fig. 4 is an interior view of a complete core showing a modified form of my device, the core being expanded ready for driving.

Fig. 5 shows the same mechanism as Fig. 4 with core collapsed and with pump attached. 80

Fig. 6 is a section on line 6-6 of Fig. 5.

Referring to Figs. 1, 2 and 3, the pile core is formed with a central member in the form of a shaft 10, either solid or hollow and provided at intervals along its length with collars 12 having outer surfaces in the shape of frustums of cones, and arranged to contact with cooperating surfaces formed on members 14 attached to the outer casing. The casing is shown as made in three sections 16 85 but may be of any desired number, two or more. The central shaft and outer casing sections are inter-connected by links 18 which serve, after collapsing has been effected, to withdraw the casing with the shaft. 90

At its upper end shaft 10 is provided with a driving head 20, into which shaft 10 is secured by threaded joint 22.

In the top of head 20 are bored three cylinders 24, each closed on top with a screw 100

plug 26. Within each cylinder 24 is a plunger 28 provided with a downwardly projecting stem 30 which passes through a drilled hole in the bottom of its cylinder and rests on the top of one of the sections 16 of the outer casting.

Formed in head 20, just below its upper surface, is the ring shaped passage 32, connected to the upper end of each cylinder 24 by a short passage 34 and having an inlet passage 36.

To the threaded outer end of passage 36 is attached a hose 38 from force pump 40 which for convenience is mounted on reservoir 42. 15 A lever handle 44 is shown for operating the pump but this is for the purpose of illustration only, as the pump may be of any type capable of creating sufficient pressure, and may be operated in any desired manner, by 20 hand or power.

In operation, the collapsed core is raised to vertical position and landed on a timber, as already described. This forces the cones 12 between members 14, thus expanding the 25 core casing and moving shaft 10 downwardly relatively to the outer casing until head 20 contacts with the upper edges of sections 16 at 46, in which position hooks 48, hinged on head 20, are engaged in eyes 50 of the several 30 sections of casing 16. The shell, which may be of paper, sheet metal, or other suitable material, is then placed on the core and the core and shell are then ready for driving.

After the pile shell has been driven and it 35 is desired to remove the core, hooks 48 are first disengaged and then pump 40 is operated to force oil, water, or any suitable liquid, through passages 36, 32 and 34 into the upper ends of cylinders 24 above plungers 28. 40 As stems 30 of plungers 28 are resting on the tops of casings 16, the reaction of the oil pressure between plungers 28 and caps 26 raises head 20 and shaft 10 relatively to the outer casing, thereby withdrawing cone wedges 12 45 from engagement with members 14, thus allowing casing 16 to collapse sufficiently to permit easy withdrawal from the pile shell. The hoisting tackle is attached to head 20, to which shaft 10 is attached at 22. Links 50 18 connect the various sections of the casing to shaft 10, therefore the entire structure is withdrawn with head 20.

A modification of the above design is shown in Figs. 4, 5 and 6, in which, instead of using a plurality of hydraulically operated plungers acting directly on sections 16 of the outer casing, I provide a single central plunger which is operatively connected to the various casing sections by toggle levers, 55 one for each section.

Each toggle comprises an upper arm 60 and a lower arm 62. Upper arm 60 is pivoted to head 20 at 64, and lower arm 62 is pivoted at 66 on a member 68 fast to the upper end 55 of a casing section 16. The lower end of each

arm 60 is provided with a nose 70 in contact with the wedge-shaped point 72 on the lower end of stem 74 extending downwardly from plunger 76 in cylinder 78. The top of cylinder 78 is closed by plug 80. Plunger 76 is normally held at the top of cylinder 78 by spring 82 surrounding stem 74.

Fig. 4 shows the core in expanded position, ready for driving, with head 20 and casing sections 16 in contact at 46 and members 14 expanded by wedges 12. Plunger 76 is at the upper end of cylinder 78, and the nose 70 of the toggle is on or near the vertical center line of head 20.

After the driving operation is finished and it is desired to withdraw the core, oil is forced between plunger 76 and cap 80 by pump 40, forcing plunger 76 downward and driving the wedge 72 between the nose ends 70 of the toggles, thus straightening the toggles and causing them to lift head 20 relatively to casing 16, thereby causing the collapse of the latter as described above.

Toggle levers 60 and 62 are relieved of any tension strain while the core is being raised with hoisting tackle, because pins 66 at the lower ends of toggle links 62 are fitted into slots 84, thus permitting the lifting strain to be carried by links 18.

I claim:

1. In a collapsible core for pile shells, in combination, an inner member, an outer member movable relatively to said inner member and comprising a plurality of sections, and an hydraulic device arranged to thrust against each of said outer sections and react against said inner member to cause movement of said section relatively to said inner member.

2. The invention set forth in claim 1 in which means is provided to support said hydraulic device on said inner member.

3. In a collapsible core for pile shells, in combination, an inner member having a head portion, an outer member comprising a plurality of sections, and a plurality of hydraulic devices supported by said head portion, each of said hydraulic devices being operable to cause an upward push on said head portion and a downward push on one of said outer sections.

4. In a collapsible core for pile shells, in combination, an inner member, an outer member comprising sections movable relatively to said inner member, a lever system operatively connecting each of said sections to said inner member, and an hydraulic device supported by said inner member, said lever systems being operable by said hydraulic device to cause relative movement of said outer sections relatively to said inner member, for the purpose described.

5. In a collapsible core for pile shells, in combination, an inner member, an outer member comprising sections movable relatively to said inner member, a toggle lever
